Richard J. Cook

UNITED STATES PATENT OFFICE.

GEORGE CALVIN AUSTIN, OF TACOMA, WASHINGTON, ASSIGNOR TO RAY E. DAY, OF TACOMA, WASHINGTON.

PISTON.

Application filed May 17, 1921, Serial No. 470,382. Renewed July 18, 1923.

To all whom it may concern:

Be it known that I, GEORGE CALVIN AUSTIN, a citizen of the United States, and a resident of the city of Tacoma, county of Pierce, State of Washington, have invented certain new and useful Improvements in Pistons, of which the following is a specification.

My invention relates to improvements in pistons and the principal object of my invention is to provide a piston made of metal having a comparatively high coefficient of expansion, such as aluminum alloy, and which is so constructed that the diametrical expansion of the piston incidental to heating in operation is controlled, thereby making it possible to minimize the diametrical expansion of the piston and making it practicable to fit the piston to an engine cylinder with less clearance than would otherwise be possible.

To obtain this, a construction is illustrated in the accompanying drawings which show two pairs of segmented bands cast within the piston walls, the latter being so slotted as to permit expansion thereof to take place circumferentially, by slipping on said bands.

A further object of the invention is to provide a piston of the above character wherein the ends of each segmented pair of bands are made to overlap each other, so that in heating, the diameter of the piston will be reduced because of the difference of coefficients of expansion of the metals employed. Varying amounts of overlap may be used, thereby making it practicable to design the piston so that in heating, the diameter will not become greater than the normal expansion of the bands; or that, in heating, the diameter of the piston will remain constant; or that, in heating, the diameter of the piston will reduce to any desirable predetermined degree within the limits of the coefficients of expansion of the metals employed in the construction of the piston.

In accomplishing these and other objects of the invention, I have provided the improved details of construction, the preferred forms of which are illustrated in the accompanying drawings, wherein—

Figure 1 is a side elevation of a piston constructed according to the present inven-

tion, partly broken away for better illustration.

Figure 2 is a transverse sectional view of the same taken on the line 2—2 in Figure 1.

Figure 3 is a section taken on the line 3—3 in Figure 2.

Figure 4 is a section on the line 4—4 in Figure 2.

Figure 5 is a view of one of the bands used in the piston.

Referring more in detail to the several views of the drawings, wherein like reference numerals designate the same or like parts—

1 designates as a whole, a piston constructed according to the present invention, and which is of the usual piston form, open at its lower end for the reception of a connecting rod and closed at its upper end by a head 2 which is reinforced by an underlying, transverse web 3 cast integrally with the head and side walls and extended diametrically across the piston. Wrist pin bosses 4 and 5 are cast integral with the walls about midway of the length of the piston, for the reception of a wrist pin to which a connecting rod may be attached; these two latter parts not being shown in the present drawing.

The skirt of the piston is provided, at opposite sides, with longitudinally directed slots 7, which extend from the open end to near the closed upper end of the piston and which, at their upper ends open into slots 8 which are directed circumferentially about the piston in a plane that is parallel with the plane of the end wall 2. These latter slots terminate above, and at opposite sides of the wrist pin bosses and at opposite sides of the web 3, so that the skirt is joined to the upper end of the piston by the web portion and by solid necks of metal directly above the bearing bosses.

To give the necessary strength and rigidity to the piston skirt and to control diametrical expansion of the piston, I have cast annular flanges 10 and 11 within the same, which are located respectively near the upper and lower ends of the slots 7, and have cast within these flanges paired segmental, expansion controlling bands 12 which preferably would be of steel, or other suitable

metal whose coefficient of expansion is relatively small as compared with that of the body forming metal. These bands are disposed in pairs in opposite relation, as shown

5 best in Figure 1, wherein the ends of paired bands are overlapped centrally between the slots 7 and are securely anchored in the skirt walls at their opposite ends.

In this construction, it is desirable that 10 except at the ends, which are to be fixed, there will be no adhesion of the bands to the piston walls and that the walls will be free to slip upon the bands. To effect this result the rings are provided at their ends 15 with heads 15, and are then given a coating of graphite paste or other suitable material and are placed in the casting mold in such position that when the piston is formed the ends of the bands will be overlapped across 20 the plane of the wrist pin bosses and the notches in the bands will receive the metal of the piston walls therein so that they are securely anchored against slippage at these points. Slippage at all other points is provided for, however, due to the coating of 25 graphite which holds the metal, when cast, away from the bands, and when the metal contracts in cooling, it permits the necessary contraction due to its compressibility, without allowing adhesion to the bands. 30

Another result obtained from the use of the graphite paste is its action as a lubricant for facilitating slippage of the walls on the bands when the piston expands or contracts.

35 In the making of such a piston, the upper, closed end would be equipped with the usual piston rings 20, and this end would be made slightly smaller in diameter than the skirt portion to make allowance for a greater expansion of this end of the piston.

40 With a piston so constructed, it is apparent that circumferential expansion of the skirt walls may be taken up in the longitudinal slots 7, and warping, that would possibly occur by a greater expansion of the head end than the skirt, is eliminated by the provision of the slots 8.

45 It is also apparent that the bands 12 will strengthen the skirt, and will not, on account of the way they are slidably contained, cause any damage or cracking of the walls by expansion or contraction.

50 It is also to be noted that the anchoring of the expansion controlling bands at opposite sides of the pistons prevents the side pressure of the piston against the cylinder walls from compressing the piston at one side and expanding it at the other side as would occur without such anchoring.

55 It will be observed that when a piston of this construction is heated in operation that the diameter of the piston will be substantially no greater than permitted by the normal expansion of the bands minus the

60 difference in the coefficients of expansion of

the metal in the bands 12 and the metal forming the piston skirt, for the distance which the bands 12 overlap.

Having thus described my invention, what I claim as new therein and desire to secure 70 by Letters Patent, is:

1. A piston of the character described, made of a metal having a relatively high coefficient of expansion, and having expansion slots in the walls thereof, and segmental 75 bands of metal, having a relatively low coefficient of expansion, disposed slidably within said walls and across said slots and anchored within said walls at their opposite ends.

2. A piston of the character described, made of metal having a relatively high coefficient of expansion, and having longitudinal expansion slots at opposite sides thereof, segmental bands, or strips, of metal, 85 having a relatively low coefficient of expansion, disposed within opposite sides of said piston with their ends overlapped, and anchored within said piston walls between said slots; said bands being slidable within the walls except at the anchored ends and extended across said slots and adapted to prevent diametrical expansion of the piston beyond that permitted by the normal expansion of the bands. 95

3. A piston of the character described, made of metal having a relatively high coefficient of expansion, and having longitudinal expansion slots at opposite sides thereof, segmental bands, or strips, of metal, having 100 a relatively low coefficient of expansion, disposed within opposite sides of said piston with their ends overlapped and having heads formed at their ends whereby they are anchored within the walls between the slots. 105

4. The method of controlling the diametrical expansion of pistons of the character described which consists of slotting the walls of said piston longitudinally, placing segmental bands, composed of metal having a 110 relatively low coefficient of expansion as compared to that of the piston, within the piston walls at opposite sides thereof with their ends overlapped, and secured at their ends only to said walls and varying the 115 extent of overlap as required to retain the diameter of the piston substantially constant regardless of any rise in temperature above normal.

5. A piston of the character described, 120 made of a metal having a relatively high coefficient of expansion and having an expansion slot in the wall thereof, and a split band of metal having a relatively low coefficient of expansion slidably disposed within said wall and extending across said slot and being anchored at its ends in said wall.

6. A piston of the character described, made of a metal having a relatively high co- 125

efficient of expansion and having an expansion slot in its skirt, and a segmental band embedded in and extending circumferentially of said skirt, said segmental band having its ends anchored in said skirt against movement, the remainder of said band being unattached to said skirt and extending across said expansion slot and adapted to prevent diametrical expansion of the piston beyond that permitted by the normal expansion of 10 the band.

Signed at Seattle, Washington, this 10th day of May, 1921.

GEORGE CALVIN AUSTIN.
